UNITED STATES PATENT OFFICE.

HARRY D. KOSTENBAUER, OF ARISTES, PENNSYLVANIA.

MINERAL OR COAL SEPARATING JIG.

1,395,716.

Specification of Letters Patent.

Patented Nov. 1, 1921.

Application filed October 2, 1920. Serial No. 414,168.

To all whom it may concern:

Be it known that I, HARRY D. KOSTENBAUER, a citizen of the United States, residing at Aristes, in the county of Columbia and State of Pennsylvania, have invented certain new and useful Improvements in Mineral or Coal Separating Jigs, of which the following is a specification, reference being had to the accompanying drawings.

10 As coal is brought from mines, it is first crushed, screened and sized or graded, and as it subsequently passes down the various chutes, slate and the like is, as a rule, picked out by hand, the coal passing on to carriers or to a dump or loaded into cars, while the slate is thrown into a chute, and passes to what is called a culm bank.

15 In picking out the slate, there is considerable coal picked out therewith, in fact some coal sticks to the slate, hence, it is the purpose of the present invention to separate this coal from the material of the culm bank.

20 The material of the culm bank is first passed through crushers, after which it is the purpose to pass this crushed material through the present form of mineral or coal separating jig, whereby the coal therein may be separated from the slate, in order to afford considerable saving.

25 The present invention further embodies the purpose, whereby the material from the culm is first deposited in a perforated pan, there being a casing for containing a large quantity of water, and means for causing a pressure of water upwardly through the perforated pan, in order to cause the coal or lighter material to come to the top and over-flow the pan and be carried off by suitable conveying means, while the slate or heavier material will automatically and periodically pass off from below into a chute, and then to a suitable conveyer.

30 It is a further aim to provide means for periodically dumping or carrying off the slate, according to the weight thereof on a suitable trap, which is counterbalanced by means of a gravity member.

35 A still further purpose is to afford plungers including check valves, for creating a pressure of water through the perforated pan, whereby the coal or lighter material may rise to the top and over-flow the pan.

40 While the design and construction at present illustrated and set forth is deemed

preferable, it is obvious that as a result of a reduction of the invention to a more practical form for commercial purposes, the invention may be susceptible of changes, and the right to these changes is claimed, provided they are comprehended within the scope of what is claimed.

45 The invention comprises further features and combination of parts, as will be herein-after set forth, shown in the drawings and claimed.

In the drawings:—

50 Figure 1 is a vertical sectional view through the improved coal or mineral separating jig constructed in accordance with the invention.

Fig. 2 is a plan view of the same.

55 Fig. 3 is a vertical sectional view on line 3—3 of Fig. 1.

Fig. 4 is a sectional view on line 4—4 of Fig. 2.

60 Referring to the drawings, 1 designates a suitable jig casing, in which partitions 2 and 3 are arranged, thereby dividing the casing into plunger receiving compartments 4 and a perforated separating pan receiving compartment 5. As shown in Figs. 1 and 3 the partition 2 is provided with openings of communication 6 between the compartments 4 and the compartment 5, whereby a pressure of water may pass from the compartments 4 into the compartment 5.

65 Rising upwardly from the ends of the jig casing are the frames 7, in bearings 8 of the tops of which a rotating driven shaft 9 is mounted. This shaft is provided with eccentrics 10 having eccentric straps 11, each of which is provided with eccentric pitman rods 12.

70 Adapted to reciprocate in the compartments 4 are pressure creating plungers 13, which have elongated openings 14. Hingedly mounted at 15 to the under-surfaces of the pressure creating plungers are flap check valves 16, adapted for controlling the water through the openings 14. For example the check valves are adapted to close on the downward movements of the pressure creating plungers 13, and open on the upward movements, the purpose being to create a pressure of the liquid in the compartment 5 on the down strokes of the plungers and to avoid a suction in the compartment 5 on the upward strokes of the plungers.

75 Oppositely disposed rods 17 are pivotally

connected at 18 to the links 19, each of which in turn is connected at 20 to a pitman 12. The lower ends of the oppositely disposed rods 17 terminate in a casting 21, 5 which comprises the diverging bars and the horizontal plates 22. The plates 22 are fastened by bolts like 23 to the pressure creating plungers, so that the plungers may move evenly in the compartments 4. It is 10 to be noted that the heads of the bolts 23 are countersunk in the under-faces of the plungers, thereby permitting check valves to completely close on the downward strokes of the plungers. It is obvious that when 15 power from any suitable source (not shown) is transmitted to the shaft 9, reciprocating movements will be imparted to the plungers, hence causing a liquid pressure to be created in the chamber or compartment 5. This 20 pressure causes the water to percolate upwardly from the perforations 25 of the stationary separating plate 26, which is mounted or secured in any suitable manner in the upper part of the compartment or 25 chamber 5. Upon this plate the material from the culm bank is first deposited. One end of the pan or plate 26 has an inclined portion 27, which causes the material to feed toward the other end of the pan or plate. 30 The other end of the pan or plate terminates in an upright wall 28 and adjacent the upper edge of this wall a suitable coal discharge chute 29 is arranged. This chute is designed to take the over-flow of the coal or lighter 35 material, which is caused to rise to the top of the material, due to the pressure of water under the pan. The end of the pan or plate adjacent the wall 28 has an opening 30, and arranged therein is a trap 31, the ful- 40 crum of which is designated by the numeral 32. Rising upwardly from the upper edges of the opposite walls of the compartment 5 are standards 33, and pivoted thereon at 34 are counter-balancing rods 35. These rods 45 have pivoted thereto as at 36, rods 37, which in turn are pivoted at 38 to the trap 31. Adjustable gravity members 39 are threaded on the counter-balancing rods, for main- 50 taining the trap normally closed. The gravity members may be otherwise mounted upon the rods, as for instance slidably, and if so mounted they may be held in different 55 positions by notches (not shown). The trap is designed to open periodically at 40, and adjacent where the trap opens a suitable slate chute or discharge 41 is provided. When the trap 31 opens, it extends in a line 60 with the bottom of the slate discharge chute 41. The trap opens, when the weight of the slate thereon overbalances the gravity member 39.

Projecting from the separator jig casing are beams 42 and 43 and the intermediate beams 44, and mounted in bearings of these 65 projecting beams are shafts 45, 46 and 47,

which carry the sprockets 48 and 49, 50 and 51. Endless conveyer chains 52 having conveyer buckets 53 pass about the sprockets 48 and 50. The coal chute or discharge 29 empties the coal direct into the elevator 70 buckets 53. Endless elevator or conveyer chains 54 pass about the sprockets 49 and 51, and also have conveyer or elevator buckets 55. The slate chute or discharge 41 has a transversely disposed portion or 75 chute 56, passing along one end of the separator jig casing, and is disposed on an inclined plane for the purpose of causing the discharge of the slate into the buckets or receptacles 55. The slate material empties from the buckets 55 on their downward movements into a chute (not shown), whereby it may be carried to a suitable dump as the buckets of the coal elevator are on their downward movements, the coal being discharged or emptied into a coal chute, which may carry the coal to cars (not 80 shown) to be loaded.

In the operation the separator jig casing is first filled with a sufficient quantity of 90 water, after which the material from the culm bank is deposited into the perforated separator pan. Power is then transmitted to the shaft 9, causing reciprocating movements to be imparted to the plungers 13. 95 Upon downward movements of the plungers the pressure of the liquid or water is created in the chamber or compartment 5, causing the water to thoroughly percolate through the perforations of the separator 100 pan, thereby causing the coal or lighter material to come to the surface, and then overflow the end wall 28 and pass off through the coal discharge chute 29. The slate being the heavier material settles to the bottom, and 105 when a sufficient amount thereof becomes located on the trap, its weight will overcome the gravity member 39 and cause the trap to open. The slate will then pass off through the chutes 41 and 56 to the slate 110 elevator. The check valves of the plungers are not only to prevent a suction and a return of the water into the compartments 4, but also prevent suction on the material to be separated, hence preventing the lighter material or coal from being drawn to the bottom of the pan. On the downward strokes of the plungers, the check valves automatically close, causing the pressure of water or liquid in the compartment 5, and hence 115 causing the lighter material to come to the surface. It is to be noted that by the provision of the openings 14, the water or liquid is allowed to flow beneath the plungers upon the upper strokes of the plungers, so that on 120 the downward strokes of the plungers, the check valves automatically close and force the water below the plungers into the compartment 5 through the openings 16, thus causing the agitation of the fluid in the com- 125 130

partment 5, necessarily causing the flow or percolation of the water or liquid upwardly and through the perforations of the pan. An agitation of this kind of the water and a percolation of the water through the pan causes the impurities or heavier material such as slate and the like a much better opportunity to separate from the lighter material or coal. By the pan being stationary, and the trap being movable as illustrated and described, the trap will operate automatically and more successfully than other devices for the same purpose, and furthermore the slate will be more efficiently separated. When the trap is closed, it prevents the escape of the water pressure, otherwise causing the water to pass through the perforations of the pan, causing the agitation of the material, and the over-flow of the coal or lighter material.

The invention having been set forth, what is claimed as useful is:—

In a mineral separator, a jig casing provided with a pan receiving separating com-

partment, a perforated pan in said compartment provided with an opening at one end, one edge of said opening having a depending wall, a chute engaging through the wall of the casing and communicating with said compartment, a trap mounted for pivotal movement in said opening for closing the same, said chute communicating with said compartment at a point opposite and below the depending wall, whereby the trap may assume an inclined position in alinement with the bottom of the chute when overbalanced by the weight of the mineral thereon, so that one edge of the trap may assume a position even with the upper surface of the pan, gravity means for holding the trap normally closed, and a second chute for carrying off the lighter particles of the mineral.

In testimony whereof I hereunto affix my signature.

HARRY D. KOSTENBAUDER.
